ARTIFICIAL EYES FOR DOLLS, DISPLAY FIGURES AND THE LIKE,
AND METHOD OF MAKING THE SAME
Filed Oct. 13, 1923

Filed Oct. 13, 1923

UNITED STATES PATENT OFFICE.

SAMUEL MARCUS, OF BROOKLYN, NEW YORK.

ARTIFICIAL EYES FOR DOLLS, DISPLAY FIGURES, AND THE LIKE AND METHOD OF
MAKING THE SAME.

Application filed October 13, 1923. Serial No. 668,281.

The invention pertains to improvements in artificial eyes for dolls and the like, and it resides more particularly in the novel method and means I have invented for applying 5 eye-lashes to these eyes. The invention also pertains to the certain features of the eye permitting my invention to be carried into effect in a preferred manner.

The eyes are connected together by a 10 bridge member to form a pair or eye-set, and each eye is usually preferably formed of an exterior shell of transparent celluloid enclosing an opaque or white shell also preferably of celluloid and bearing a representation 15 of the iris, and this combined shell, constituting the exterior of the eye, is preferably mounted upon a hemispherical metal shell to be adjustably secured on a transverse rod or bridge which in use has one of the 20 eyes at each end thereof and at its middle portion is pivotally mounted upon a supporting hanger or bracket and also connected with means for effecting a rolling motion of the eyes to close 25 when the doll is reclined and to open when the doll is restored to vertical position. The iris is exposed at the front and is preferably slightly below the center of the hemispherical shells so that when the doll is reclined 30 the eye may rather quickly close or disappear within the head of the doll.

In carrying out my invention I preferably provide an eye-lash member which consists of a suitable width of parallel fibres or 35 strands arranged close together and secured at their end portions in fixed relation to each other by means of paper or other thin strips secured upon one side thereof and extending at right angles to the length of the 40 fibres or strands. This eye-lash member I utilize for providing the artificial eye with eye-lashes, and in respect to this part of the invention I cut a transverse slit through the 45 front wall of the exterior shell of the eye and above the iris representation exposed thereon and insert one end of the eye-lash member carrying its binding strip through this slit and preferably press the binding strip on said end upwardly against the 50 inner surface of the exterior shell of the eye, causing the same to adhere thereto by adhesive or other means. The positioning of one end of the eye-lash member within the exterior portion of the eye leaves the other

end of the eye-lash member exposed outwardly beyond the eye, and this portion of the eye-lash member is trimmed down along an arcuate line crossing the member to such extent as may be desired for leaving the fibres or strands exposed at the front of the 55 eye of proper length to constitute the eye-lashes. The eye-lashes will appear directly above the iris of the eye, and when the exterior portion or shell of the eye is mounted upon the metal shell or base, the eye-lashes 60 will become permanently secured in place.

The invention will be fully understood from the detailed description hereinafter presented, reference being had to the accompanying drawings, in which:

Fig. 1 is a front view of an eye-set adapted for introduction into the head of a doll in a well understood manner and embodying my invention;

Fig. 2 is a vertical section through the 75 same, taken on the dotted line 2—2 of Fig. 1, and showing the iris offset from the center of the eye;

Fig. 3 is a top plan view of one of the eyes, the bridge rod being partly broken away;

Fig. 4 is a central vertical section, on an enlarged scale and partly broken away, through one of the eyes and taken on the dotted line 4—4 of Fig. 1;

Fig. 5 is a perspective view of the eye-lash 85 member which I make use of in providing the eyes with eye-lashes;

Fig. 6 is an enlarged central vertical section through the two outer shells of one of the eyes and illustrates the preliminary step 90 in introducing the eye-lash member thereto;

Fig. 7 is a top view, on a smaller scale, of the same, and by the arcuate broken line indicates the line on which the eye-lash member is trimmed-off as the final step in forming the eye-lashes, and

Fig. 8 is an enlarged central vertical section through the two outer shells of the eye and illustrates the manner of securing the inner end of the eye-lash member, shown in 100 Figs. 5 and 6, preparatory to the trimming off of the strands constituting the eye-lashes on the arcuate broken line indicated in Fig. 7.

In the drawings, 10 designates the two 105 eyes of a pair of eyes, said eyes being supported upon a transverse rod or bridge 11 which is pivotally mounted in a bracket or

hanger 12 and has rigidly connected with it a rod 13 suspending a weight 14, which acts when a doll containing the eye-set is reclined, to turn the rod 11 and therethrough 5 effect a closing motion to the eyes 10 and which also acts when the doll is returned to vertical position, to effect an opening movement of the eyes. The rod 11, hanger 12, rod 13 and weight 14 are disclosed in Fig. 10 11 of Letters Patent No. 1,433,901, granted to me on October 13, 1922, and hence these mechanical features do not require specific description.

The eyes 10 correspond with each other 15 and each eye comprises an inner or base hemispherical metal shell 15 and an exterior shell preferably comprising, as illustrated, an outer transparent thin celluloid shell or layer 16 and a thin intermediate opaque 20 shell or layer 17 upon which the iris is imprinted and which iris becomes exposed through the outer shell, as shown. The shells 15, 16 and 17 are assembled and nested in a well-known manner, and the eyes 25 formed therefrom may be secured upon the ends of the bridge or rod 11 by means of screws 18 passing through threaded holes in the backs of the metal shells 15 and engaging at their forward ends the rod 11, 30 as shown in Fig. 4. As illustrated in Fig. 2 of the drawing the iris 19 of the eye is not centrally disposed with respect to the hemispherical shells 16, 17, but is nearer to the lower edge of said shells than it is to 35 the upper edge thereof, this being for two purposes, one being to throw the iris directly to the front when the eye is inclined as shown in Figs. 2 and 4 and the doll is upright, and the other being to effect a 40 quick concealment of the iris when the doll is reclined and the eyes roll downwardly along their sockets within the head of a doll. When the iris is disposed in the manner described there is less of the white of 45 the eye below the iris to roll into concealment than there would be if the iris were directly at the center of the shells 16, 17 and said shells were not normally inclined to the position indicated in Figs 2 and 4. 50 I regard the location of the iris below the center of the shells 16, 17 as quite important in securing proper action in artificial eyes for dolls and also as important when said eyes are provided with eye-lashes, 55 since with such location of the iris and the inclination hereinbefore described of the eye-shell, the eye-lashes can meet the lower lids of the eyes without necessitating undue rolling action of the eyes.

60 An essential feature of the present invention relates to the eye-lashes and the manner of securing them to the artificial eye, and with respect to this part of my invention I provide an eye-lash member 20, shown in Fig. 5, which I make use of in equipping

the eye-shells with eye-lashes. The eye-lash member 20 comprises a series of parallel closely arranged fibres or strands 21, these fibres or strands 21 being arranged to form a flat band and being connected together 70 at their ends by spaced apart pliable strips 22 of thin paper, textile fabric or the like secured by an adhesive on one side of the band at the ends thereof, both strips 22 preferably being on one side of the band of 75 fibres or strands. In order to utilize the eye-lash member 20 I cut a transverse slit 23 preferably through the thickness of the eye-shell member from its exterior to the interior, and in the specific embodiment of 80 the invention, through the front wall of the eye-shell, made up of the parts 16, 17, from front to rear, on a line directly above the iris 19, or in the appropriate position for an eye-lash member, the general plane of 85 said slit being tangential to the geometric center of the eye-shell. In applying the eye-lashes to the eyes I insert one end of the eye-lash member 20 inwardly through the slit 23, as shown in Fig. 6, and thereafter 90 I press the thin inner strip 22 of the member 20 upwardly against the inner shell 17 and secure it to said shell by an adhesive, as will be understood on reference to Figs. 4 and 8. Hence, the eye-lash member is partly 95 within the eye-shell or eye-shell member and partly without the same. After the inner end of the eye-lash member 20 has been secured within the upper portion of the shell 17, I trim off the projecting portion of said 100 member, which intervenes the spaced strips 22, 22, along an arcuate line, indicated at 24 in Fig. 7, to leave projecting outwardly from the slit 23 the eye-lashes 25, the length of the eye-lashes 25 being determined by the 105 size of the eyes and the particular effect I desire to secure. When the eye-lash member is trimmed off along the arcuate line 24 the eye-lashes are left projecting outwardly from between the slightly separated 110 upper and lower edge walls of the slit 23 and may be pressed upwardly to a slight extent, if desired, so as to impart a curvature to the eye-lashes. After the surplus portion of the member 20 has been trimmed off to 115 leave the eye-lashes 25 of the desired length, it will be found that by reason of the upward bending of the inner portion of the member 20 against the upper portion of the shell 17, the eye-lashes will tend to 120 spread out radially in the manner indicated in Fig. 3, and in this way come closer to approximating the appearance of human eye-lashes. The slot 23 is directly above the iris 19 and above the horizontal center of 125 the hemispherical shell formation of the eye and hence the lower wall of the slot stands forwardly beyond the upper wall thereof, as shown in Fig. 4, and affords a seat for the full width of the lever of fibres 130

- constituting the eye-lashes. The eye-lashes are housed between the upper and lower walls of the slot 23 and the inner ends of the lashes are concealed within the shell structure of the eye. The slot 23 is very important in properly maintaining the eye-lashes for a long period of time and when the slot is made use of the eyes above the lashes may be left plain to receive such coloring matter for the eye-lids as the manufacturer of the dolls may see fit to apply thereto. It is a matter of some difficulty to provide an artificial eye with eye-lashes and I consider the method just described of providing the eyes with eye-lashes, as important, both from a manufacturing standpoint and in producing eye-lashes approximating in appearance the eye-lashes of the human eye. By first constructing the eyelash member 20 and then applying the same to the eye-shell as described, the flexible fibres or strands may be readily handled and secured in position, the means securing them being concealed within the eye-shells. In the use of the eye-set shown in the drawings, the manufacturer of the dolls will color the upper ends of the eye-shells above the eye-lashes to imitate eye-lids, the coloring material used corresponding with the coloring matter applied upon the face and forehead of the dollhead. I therefore leave the eye-shells above the eye-lashes plain and smooth so that they may receive such coloring matter as the manufacturer of the doll may elect to place thereon.
- It is to be noted that the metal base shell 15 constitutes a retaining member in engagement with that portion of the eye-lash member which is within the eye-shell member, and serves in holding the eye-lash member attached to the eye-shell member, the rear portion of said retaining member constituting connecting means to connect the eye-shell member with a supporting member, such, for example, as the rod or bridge 11.
- What I claim as my invention and desire to secure by Letters-Patent, is:
1. Artificial eyes for dolls and the like, said eyes each being substantially hemispherical in outline and of shell structure and presenting an iris and having eye-lashes, said shell structure being formed with a transverse slit extending through the front wall of the structure from front to rear above the horizontal center thereof and above the iris, and the eye-lashes composed of a layer of strands secured at one end within the structure and extending through the slit between the upper and lower edge walls thereof.
  2. An artificial eye for dolls and the like comprising an eye-shell structure formed with a slot extended through the front wall from front to rear thereof, and eye-lash strands in the form of a band at one end secured within the shell structure and projected forward through the slot in the front-wall between the upper and lower edge walls thereof.
  3. An eye structure, comprising an eye-shell member having a slit formed through its thickness from the exterior to the interior thereof, and an eyelash member in said slit and projecting outwardly therefrom. 70
  4. An eye structure, comprising an eye shell having a slit therein opening through the front face thereof, and an eyelash member in said slit and projecting forwardly therefrom to comprise an eyelash attached to the eye shell. 80
  5. An eye structure, comprising an eye-shell member having a slit formed through its thickness from the exterior to the interior thereof, and an eyelash member projecting through said slit and being partly within and partly without the said eye-shell member. 85
  6. An eye structure comprising an eye shell member having a slit formed through its thickness from the exterior to the interior thereof, and an eye lash member projecting through said slit and being partly within and partly without the said eye shell member, and means engaging the portion of the eye lash member within the eye shell member to retain the eye lash member in position. 90
  7. An eye structure comprising an eye shell member having a slit formed through its thickness from the exterior to the interior thereof, an eye lash member projecting through said slit and being partly within and partly without the eye shell member, and a retaining member engaging the portion of the eye lash member which is within the eye shell member to hold the eye lash member in position and having a part to hold the eye shell member connected with a suitable support. 100
  8. An eye structure comprising an eye shell member having a slit formed through its thickness from the exterior to the interior thereof, an eye lash member projecting through said slit and being partly within and partly without the eye shell member, and connecting means to hold the eye shell member connected with a suitable supporting member, and said connecting means having a part also serving in holding the eye lash member in position. 110
  9. An eye structure, comprising a base shell and two outer shells mounted upon the base shell, said outer shells consisting of a transparent shell and an inner shell fitting within the transparent shell and bearing the representation of an iris visible through the transparent shell, said two outer shells having slits therethrough, and eye lashes projecting through said slits and having their 115
  - 65 strands in the form of a band at one end

- inner ends held between the base shell and the inner shell.
10. An artificial eye for dolls and the like comprising an eye shell structure formed 5 with a slit extending through the wall of the eye shell from the exterior to the interior thereof, and eye lash strands in the form of a band secured at one end within the shell structure and projecting outward- 10 ly through the slit between the upper and lower edges of said slit.
11. As an article of manufacture, a forming member for the eye lashes of artificial eyes, said eye lash forming member com- 15 prising a series of strands arranged lengthwise side by side, and strips secured to said strands and spaced apart, the parts of the strands between said strips adapted to be severed in forming eye lashes.
- 20 12. As an article of manufacture, an eye lash forming member from which to form eye lashes upon artificial eyes, said eye lash forming member comprising a series of strands arranged lengthwise side by side, 25 and a pair of strips secured to said strands spaced apart adjacent the opposite ends of the strands so as to leave the intervening parts of the strands free of said strips, said eye lash forming member being thus adapt- 30 ed to be connected with the artificial eye by having either one of said strips inserted through a slit of the eye and secured within the eye, and the strands between the eye and the second strip being adapted to be 35 trimmed off to leave the desired length of eye lash on the eye.
13. As an article of manufacture, a shell for artificial eyes, said shell having a slit formed through its thickness and said slit 40 being in an appropriate position to accommodate an eye lash member.
14. As an article of manufacture, a shell for artificial eyes, said shell having the representation of an iris thereon and having 45 a slit formed through its thickness, above the representation of the iris and in appropriate position to accommodate an eyelash member.
15. As an article of manufacture, a shell 50 for artificial eyes, said shell having the representation of an iris thereon and having a slit formed through its thickness, above the representation of the iris and in an appropriate position of an eye lash member, 55 the general plane of said slit being tangential to the geometric centre of the shell.
16. As an article of manufacture, a shell for artificial eyes, said shell being composed of celluloid and being a semi-spherical 60 shape and having a slit formed through its thickness and in the appropriate position of an eye lash member.
17. As an article of manufacture, a shell 65 for artificial eyes, said shell being semi-spherical in shape and being formed with a slit through its spherical outer surface in the appropriate position of an eye lash member.
18. As an article of manufacture, a shell for artificial eyes, said shell being formed 70 of a plurality of semi-spherical layers nested together, and said layers having slits therethrough in the appropriate position of an eyelash member.
19. As an article of manufacture, a shell 75 for artificial eyes, said shell being formed of two semispherical members nested together, and at least one of said members having a slit formed through the material thereof in the appropriate position of an eye 80 lash member.
20. As an article of manufacture, a shell for artificial eyes, said shell being formed of two semispherical members nested together, one of said members having the representa- 85 tion of an iris thereon, and there being a slit formed through one of said members adjacent the upper edge of said iris in the appropriate position of an eye lash member.
21. As an article of manufacture, a shell 90 for artificial eyes, said shell being formed of two semispherical layers nested together, the outer layer being transparent, the inner layer having the representation of an iris thereon visible through the outer layer, and the outer layer having a slit therethrough adjacent to the upper edge of said iris in the appropriate position of an eye lash member.
22. As an article of manufacture, a shell 95 for artificial eyes, said shell being formed of two semispherical layers nested together, the outer layer being of transparent material, the inner layer having the representation of an iris thereon visible through the material of the outer layer, and said two layers having slits therethrough arranged to accom- 100 modate an eye lash member adjacent the upper edge of said iris.
23. As an article of manufacture, a shell 105 for artificial eyes, said shell being formed of a plurality of semispherical shells of celluloid nested together, and said shells each having a slit formed through the material thereof arranged collectively to accom- 110 modate an eye lash member in the appropriate position for such member.
24. An eye structure comprising an eye shell member having a slit formed through its thickness from the exterior to the interior 115 thereof, an eye lash member projecting through said slit being partly within and partly without the eye shell member, and a semispherical shell nested within the mentioned eye shell member serving as retaining means engaging the portion of the eye 120 lash member within the eye shell member to retain the eye lash member in position.
25. The herein described method of pro- 125 ducing artificial eyes having lashes thereon,

which method consists in providing an eye-shell member, forming a slit through said eye-shell member in the appropriate position for an eye lash, providing an eye lash member having eye lash strands held together by a retaining strip, inserting the retaining strip through said slit so that the eye lash member is disposed with its eye lash strands projecting outwardly through the slit and with said retaining strip within the eye-shell

member, securing the eye lash member against displacement, and then trimming off the outer ends of the eye lash strands to leave a desired length thereof projecting from the slit.

Signed at New York City, in the county of New York and State of New York, this 11th day of October, A. D. 1923.

SAMUEL MARCUS.
